UNITED STATES PATENT OFFICE.

ALONZO J. SIMMONS, OF INDIANAPOLIS, INDIANA.

APPARATUS FOR INJECTING AIR AND STEAM INTO FURNACES.

SPECIFICATION forming part of Letters Patent No. 251,740, dated January 3, 1882.
Application filed June 8, 1881. (No model.)

To all whom it may concern:

Be it known that I, ALONZO J. SIMMONS, of Indianapolis, Marion county, Indiana, have invented a new and Improved Apparatus for Injecting Air and Steam into Furnaces; and I do hereby declare that the following is a full, clear, and exact description of the same.

It is well known that a more perfect combustion of fuel in furnaces, and consequent reduction in the volume of smoke produced, is obtained by injecting suitable quantities of air and steam into the furnace, commingled in proper portions.

The object of my invention is to provide simple and effectual means for accomplishing the results above named, and also in securing the most perfect distribution of the oxygenated gases over the bed of heated coals, to bring them in direct contact with the gases of combustion while heated to the required degree to support combustion; and the improvement consists, first, in combining a series or nest of air tubes or nozzles with a steam-drum so that the air-tubes will pass diametrically through the steam-drum, which is connected to the steam-space of the boiler by a single pipe, and so that each of the air-tubes will communicate with the steam-drum in such manner that the air can be drawn through the tubes and forced into the furnace by the action of the steam; second, in combining a series of air pipes and nozzles with a steam-drum so that they will pass diametrically through it and will protrude one into the other in such manner that a space will be left between them, through which steam may pass from the interior of the drum in a tubular sheet into and through the nozzle, in such manner as to draw air through the pipe encircled by the steam and force it into the fire or combustion chamber, the relative quantities of steam and air being adjusted by screw-threads upon the thimbles, air-pipes, nozzles, and steam-drum; third, in arranging a nest or series of injection-nozzles relatively with a deflector-plate secured to the inner wall of the furnace, which will serve to deflect the oxygenated gases upon the entire mass of fuel at such distance from its surface as to insure its proper distribution and the complete combustion of the entire body of coal upon the grates.

In the accompanying drawings, Figure 1 is an elevation showing the inner side of the fur-

nace; Fig. 2, a transverse section in the line *x* *x* of Fig. 1, and Fig. 3 a horizontal section in the line *y* *y* of Fig. 2.

The furnace is formed in a well-known manner, with outer plates, A, and inner plates, A', held at a suitable distance apart by stay-bolts B, and provided with an angle-iron, C, secured to the face of the inner plate, that serves to support the grate-bars of the furnace in an effectual manner. A cylindrical drum, D, closed at one end and communicating at the other end by pipes D' with the steam-space of the boiler, is arranged horizontally alongside of the outer wall of the furnace, and is supported by a strap or straps, E, secured to the outer plate, A, of the furnace-casing. The center line of the drum D is arranged in a horizontal line which will come a few inches above the surface of the coals upon the grate-bars, and the drum is connected to a series of nozzles, E', in the said central line, at suitable distances apart, that pass through and closely fit the interior of hollow stay-bolts B', so that gases passing through the nozzle will be diverted over the surface of the burning coal. The nozzles E' are provided each with a shoulder, e, some distance from its outer end, that is screw-threaded and fits a corresponding thread in the drum D. The inner end of each nozzle E' passes horizontally across the steam-drum to its central part, and is provided with a conical central opening into which the end of a correspondingly-coned pipe, F, projects a sufficient distance to leave an annular conical space, f, between them, which space is left open to communicate between the interior of the drum D and the fire-chamber. The pipe f passes through the drum D in a horizontal line immediately opposite the nozzle E', so that the nozzle and pipe will pass diametrically through the drum. The pipe F is open at its outer end to allow the outer air to be freely drawn into it and forced through the nozzle E' by the steam passing in a rapid current through the annular space f around the conical end of the pipe. The outer end, F', of the pipe F is cylindrical, and is screw-threaded to fit into corresponding threads in the drum D. A nut, F², is also screw-threaded upon its inner surface, and also upon one end of its outer surface, by which means an adjustable steam-pipe connection is formed between the pipe F and the

drum D, by which means more or less steam can be admitted around the pipe F into the furnace by first slackening back nut, F², and turning pipe F in one direction or the other, as desired, 5 to increase or decrease the amount of steam admitted to the furnace, and then by screwing up back nut, F², to make a steam-tight joint.

A deflector-plate, G, of angle-iron, is secured to the inner wall, A', of the furnace at a down- 10 wardly-inclined angle at a point immediately above the nozzle-opening e² of the nozzles E', so that as the mingled air and steam issues in a jet from the nozzles it will be shed downwardly in a fan-shaped sheet to project across the flame 15 or radiant gases in the process of combustion upon the surface of the coal, and be diverted to the surface of the coal in the central part of the grate, at the point where the greatest amount of oxygen is consumed and is the most 20 remote from the ordinary supplies. The air is sufficiently heated by the steam to prevent it from chilling the flame upon the coals, and by its admixture with a suitable amount of steam the commingled gases are expanded to a sufficient extent to admit of a rapid combustion of 25 the carbonated gases of the furnace by their union under suitable conditions with the oxygenated gases injected into the furnace.

The deflector G may be formed of a single

plate extending over all of the nozzle-openings; 30 or a number of deflector-plates may be employed, arranged one above each of the openings.

The angle-plate C, upon which the ends of the grate-bars are supported, extends entirely 35 across the surface of the inner plate, A', and operates to effectually check cold currents of air from creeping up the sides of the furnace and chilling the flame.

I claim as my invention and desire to secure 40 by Letters Patent—

The combination, with the furnace, of the steam-drum D, the steam-nozzle E', one of whose extremities extends within the hollow stay-bolt B', the other having a conical mouth 45 extending half-way through the drum, stay-bolt B, air-pipe F, extending a short distance inside the mouth of said steam-nozzle, and the nut F², having outside threads corresponding with other threads in the side of the steam- 50 drum and inside threads corresponding with other threads upon the outside of the air-pipe, substantially as and for the purposes described.

ALONZO J. SIMMONS.
